UNITED STATES PATENT OFFICE.

RALPH A. WAKEFIELD, OF SACRAMENTO, CALIFORNIA, ASSIGNOR OF ONE-FOURTH TO ERNEST A. BOUTWELL AND ONE-FOURTH TO WILLIAM M. CAMPBELL, OF SACRAMENTO, CALIFORNIA.

OIL-CAN.

1,046,515.

Specification of Letters Patent. Patented Dec. 10, 1912.

Application filed May 21, 1912. Serial No. 692,736.

To all whom it may concern:

Be it known that I, RALPH A. WAKEFIELD, a citizen of the United States, residing at Sacramento, in the county of Sacramento, 5 State of California, have invented certain new and useful Improvements in Oil-Cans; and I do declare the following to be a full, clear, and exact description of the same, such as will enable others skilled in the art 10 to which it appertains to make and use the same, reference being had to the accompanying drawings, and to the characters of reference marked thereon, which form a part of this application.

15 This invention relates to improvements in oil cans and particularly to an improvement or addition to the spout of the oil can whereby the same will not leak or drop any oil until it is absolutely desired that it 20 shall do so. In other words, the can may be tipped over or held in an inverted position but no oil will pass therefrom until the same is positioned at a point where it is desired to place the oil and then the can 25 is operated in the usual manner as other cans now commonly in use and thereupon the oil will pass from the can and immediately upon a discontinuance of the pressing of the bottom of the can the oil supply 30 is automatically shut off.

A further object of the invention is to produce a simple and inexpensive device and yet one which will be exceedingly effective for the purposes for which it is de- 35 signed.

These objects, I accomplish by means of such structure and relative arrangement of parts as will fully appear by a perusal of the following specification and claim.

40 The figure of the drawing shows the sectional view of an oil can with my improved structure therein.

Referring now more particularly to the characters of reference on the drawings the 45 numeral 1 designates an oil can showing the usual flexible bottom 2 and the usual threaded top 3 to receive the spout 4.

In providing my improved invention I dispose a small plate or band 5 across the

bottom of the spout the same being of such 50 a width as to permit a passage-way on both sides of it into the spout. I then provide a vertical pin or rod 6 which is provided with a cross-head 7 adapted to rest on a chamfer 8 in the top of the spout 4 to form 55 a normal closure for said spout. Said rod 6 then projects through the plate 5 and is provided with a threaded end 9 on which is mounted a threaded sleeve 10 having a projecting flange 11 at its upper end. 60

A spring 12 is interposed between the flange 11 and the member 5, the tension of which spring normally holds the cross-head 7 closed against the chamfer 8. This structure will therefore, keep the oil can closed 65 until it is desired to have oil pass therefrom and then the bottom tube is pressed in the usual manner which will press against the sleeve 10 and force the rod 6 and cross-head 7 outward. This action will open the end of 70 the spout 4 permitting the oil to pass therefrom. When pressure is taken off of the bottom tube the spring 12 will then again force the member 7 into closed position. By means of the threaded sleeve 10 the length of the rod 75 6 may be changed in order that the same will always fit with the proper adjustment against the bottom tube in order to insure perfect operation.

From the foregoing description it will be 80 readily seen that I have produced such a device as substantially fulfills the object of the invention as set forth herein.

While this specification sets forth in detail the present and preferred construction of the 85 device, still in practice such deviations from such detail may be resorted to as do not form a departure from the spirit of the invention.

Having thus described my invention what 90 I claim as new and useful and desire to secure by Letters Patent is:

A device of the character described comprising an oil can having a spout, a plate disposed across the bottom of said spout, a 95 vertical pin projecting through said can and said spout, a crosshead on the upper end of said pin, said spout being provided with a

chamfer at its upper end to receive said crosshead, said rod being provided with a threaded portion on its lower end; a threaded sleeve mounted on said threaded portion, 5 a projecting flange on said sleeve, and a spring interposed between said flange and said plate, as described.

In testimony whereof I affix my signature in presence of two witnesses.

RALPH A. WAKEFIELD.
